UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,174, dated March 6, 1888.

Application filed January 11, 1888. Serial No. 260,451. Term of patent 3½ years.

To all whom it may concern:

Be it known that I, MARY TURNER, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a basque and a round walking skirt. The skirt exhibits a deep front drapery that falls in curves and jabot folds below the right hip and in a pouf below the left hip and displays draping plaits extending from the belt all across; a full back drapery that falls deeper at the sides than at the cen-

ter and displays loopings at the center. The basque displays full fronts flaring above the bust, revealing a vest in V shape, and exhibiting shirrings along the shoulder edges and in clustered rows at the bottom; a postilion back falling in two box-plaits below the waistline; coat-sleeves, and a standing collar.

What I claim as my invention, and desire to secure by Letters Patent, is—

The design for a lady's costume, as shown in the engraved prints accompanying this specification.

MARY TURNER.
